UNITED STATES PATENT OFFICE.

FRANK VOGEL, OF CHICAGO JUNCTION, OHIO

COIN TUBE AND TRAY.

1,139,604.

Specification of Letters Patent. Patented May 18, 1915.

Application filed April 7, 1914. Serial No. 830,190

To all whom it may concern:

Be it known that I, FRANK VOGEL, a citizen of the United States, residing at Chicago Junction, in the county of Huron and State of Ohio, have invented a new and useful Coin Tube and Tray, of which the following is a specification.

This invention relates to a combined coin tube and tray.

10 An object of the present invention is to provide a coin receptacle in which coins may be deposited, the length of the column of coins being an indication of the total number therein and therefore the amount of 15 money within the tube.

A further object is to provide a receptacle including a removable tray, the coins being deposited in the tray which forms a convenient holder therefor such as may be used 20 upon a desk for the making of change, etc., and which tray is insertible within the outer shell of the receptacle and may be sealed therein, thus preventing malicious tampering with the device.

25 With the foregoing and other objects in view which will appear as the description proceeds, the invention resides in the combination and arrangement of parts and in the details of construction hereinafter described and claimed, it being understood 30 that changes in the precise embodiment of the invention herein disclosed, can be made within the scope of what is claimed, without departing from the spirit of the invention.

35 In the drawings accompanying this specification and forming a part thereof, the preferred embodiment of my invention is illustrated, in which:—

Figure 1 is a view in perspective of the 40 tray and disclosing the same with the hinged key turned down which prevents its tipping or rotation, which would result in the spilling of the coins therefrom. Fig. 2 is a view in elevation of the receptacle with 45 the tray in position within the outer shell and sealed thereto. Fig. 3 is an end view of the device. Fig. 4 is a similar view taken from the opposite end. Fig. 5 is a cross sectional view taken on the line 5—5 of Fig. 2.

50 Referring to the drawings in which similar reference numerals designate corresponding parts throughout the several views, 5 represents a semi-cylindrical pipe which constitutes the body portion of the 55 tray.

A plurality of partitions 6 extend across

the semi-cylindrical body portion 5 and divide the tray into a plurality of compartments, each of which holds a predetermined number of coins and therefore a predetermined amount in value. An end plate 7 60 which is circular in outline is provided with the key 8 secured thereto by the hinge 9. The opposite end plate 10 is provided with the cylindrical projection 11 through which 65 extends the opening 12. The opening 12 is provided for the reception of a sealing wire, thus indicating whether or not the device has been tampered with in transit.

The outer shell 13 is of such diameter as 70 to receive the inner semi-cylindrical pipe 5 therein and to snugly engage the same. The end plate 7 is of sufficient diameter so as to enter within the shell or casing 13 and extend some little distance therein. The end 75 plate 7 is provided with the outwardly extending peripheral projection 14 which enters within a slot 15 formed in the end of the casing, which slot communicates with a second transversely extending slot 16 into 80 which the projection 14 rotates, thus securely locking the tray against accidental displacement from the casing.

The casing is provided with a number of 85 openings offset and which openings provide means whereby the interior of each compartment defined between the partitions 6, is rendered visible. A suitable scale is inscribed upon the outer shell or casing and is graduated in the terms of the amount of 90 money represented by the coins contained within the tray. The end wall 18 of the casing is provided with the opening 19 extending therethrough and through which extends the projection 11 when the tray is 95 positioned within the casing. The projection 11 extends through the said opening to such an extent as to be accessible and through which is passed the wire 20, the latter extending through suitable openings 100 in the casing and to which wire is applied the seal 21, thus preventing the withdrawal of the tray without giving indication of the same. The end wall 18 is provided with the spring 22 which resiliently holds the tray in 105 place in a locked position.

The key 8 is of such dimensions that it folds up against the end plate 7 and when so positioned extends within the end of the casing as illustrated in Figs. 2 and 4. When 110 it is desired to withdraw the tray, the said key is turned outwardly, affording a suit-

able grip for the rotation of the tray, so that the projection 14 thereof will register with the slot 15, allowing the withdrawal of the tray, it being noted, that the wire and seal 5 are first removed. When the tray is withdrawn from the shell, the key is turned downwardly as illustrated in Fig. 1 and affords a rest and provides that the tray will remain in an upright position as illustrated 10 in Fig. 1. The device thus forms a convenient means for making change and a handy receptacle and convenient deposit for coins in banks and similar institutions. At the close of the business day, the tray is inserted 15 in the casing and the scale upon the casing will indicate the amount of money the device contains. The entire device may then be placed within a safe or affords a handy receptacle for the shipping of such 20 moneys. The device may be made of such size as to accommodate any different species of coins, as desired.

Having thus described my invention, what I claim is:—

- 25 1. A tray for money receiving receptacles comprising a segmental cylindrical pipe, a circular end wall carried by said pipe, closing one end thereof, and a key hingedly secured to said end wall, foldable thereagainst and foldable therebeneath, said key when disposed in the latter position preventing the rotation of said tray when positioned upon a plane surface.
- 30 2. A device of the character described, comprising an outer shell with a broken slot extending in from one end thereof, a tray insertible within said shell and adapted to receive coins therein, a projection carried

by the end plate of said tray adapted to enter within the said broken slot and prevent the accidental detachment of said tray from said shell, and a key hingedly secured to said end plate providing for the manual rotation of said tray to the locked position of said projection within said slot, said key movable beneath said tray for the supporting of the same in a non-rotatable manner upon a plane surface.

3. A device of the character described, comprising a tray, a casing adapted to receive said tray therein, means carried by the tray for locking the same in said casing, said means further adapted to maintain said tray in a normal upright position when detached from said casing, and resilient means positioned within said casing, contacting with the end wall of the tray and resiliently holding the same in locked position.

4. A device of the class described, comprising a segmental pipe, a casing receiving said pipe therein, said casing provided with an aperture in the end wall thereof, said segmental pipe provided with outwardly extending projections extending through said casing end wall aperture, and means engaging the ends of said projections, holding the pipe within said casing.

In testimony that I claim the foregoing as my own, I have hereto affixed my signature in the presence of two witnesses.

FRANK VOGEL.
